HAIRPIN

Clara Olive Bergstrom, Portland, Oreg.

Application March 14, 1944, Serial No. 526,381

2 Claims. (Cl. 132—52)

This invention relates generally to the art of hair dressing, and particularly to an improved form of hairpin.

The main object of this invention is to provide an exceedingly simple and efficient means for preventing the loss or accidental dislodgement of hairpins after they are once placed in position in the hair.

The second object is to provide a hairpin of the class described which will be inexpensive to manufacture, easy to apply and remove, and not injurious to the hair or uncomfortable to the wearer.

These and other objects will become more apparent from the specification following as illustrated in the accompanying drawing, in which:

Fig. 1 is a side elevation of a hairpin equipped with my improvement.

Fig. 2 is an enlarged fragmentary view showing a side elevation of the preferred form of the device.

Fig. 3 is a section taken along the line 3—3 in Fig. 2.

Fig. 4 is a view similar to Fig. 2 showing how the barb lies down when a pull is exerted against the pin greater than the force required to insert it.

Fig. 5 is a fragmentary view showing a modified form of the device.

Fig. 6 is a transverse section taken along the line 6—6 in Fig. 5.

Similar numbers refer to similar parts throughout the several views.

Referring in detail to the drawing, there is shown a common form of hairpin 10 whose side members 11 may or may not be waved, as is the common practice. My improvement on the commonly used existing type of pin consists of a flexible barb 12, which is preferably natural or synthetic rubber and a part of a tubular section 13 and inclined with relation thereto, it being

desirable to have the base 14 of the barb 12 somewhat removed from the end 15 of the tubular section 13 in order to provide a hair engaging socket 16, and prevent the hair from being caught in the above junction of the members 11 and 13. The tubular section 13 is either vulcanized to the member 11 or frictionally held thereon. In the form of the device shown in Figs. 5 and 6 a strip of rubber or flexible material 17 is formed into the shape of a U, whose sides 18 and 19 are inclined with relation to the hairpin 20. It is desirable to coat the side members 21 with an adhesive 22 for the purpose of positioning the members 18 and 19 and again for the purpose of preventing hair from becoming caught in the acute angle between members 19 and 21.

While only one barb is illustrated in use on a single pin, it is obvious that more can be employed if desired without departing from the spirit of this invention.

While I have thus illustrated and described my invention, it is not my intention to be limited to the precise form shown herein but I do intend to cover all such forms and modifications thereof as fall fairly within the appended claims.

What I claim as new and desire to protect by Letters Patent is:

1. A rubber barb for hairpins consisting of a perforated body having a laterally extending barbed portion inclined with relation to the axis of the perforation in the barb.

2. The combination of a barrel shaped rubber body having a cylindrical opening formed therethrough along the axis of the body, a U-shaped hairpin having one of its legs projecting through said body and a flexible barb projecting from one side of said body and pointing toward the closed end of said pin, said barb forming an acute angle with relation to the closed end of said pin.

CLARA OLIVE BERGSTROM.
